CLAIM

The ornamental design for a combined bottle and stopper therefor, substantially as shown and described.

DESCRIPTION

FIG. 1 is a top plan view of a combined bottle and stopper therefor, showing my new design;

FIG. 2 is a front elevational view thereof, the rear elevational view being the same;

FIG. 3 is a side elevational view thereof, the opposite side elevational view being the mirror image thereof; and

FIG. 4 is a bottom view thereof.
